US00D555652S

(12) **United States Design Patent** (10) **Patent No.:** **US D555,652 S**
Kitamura et al. (45) **Date of Patent:** **** Nov. 20, 2007**

(54) **DOCUMENT SCANNER**

(75) Inventors: **Teruhiko Kitamura**, Tachikawa (JP);
Minoru Sashida, Saitama (JP);
Kazuhikde Sigiyama, Yokohama (JP)

(73) Assignee: **Canon Denshi Kabushiki Kaisha**,
Chichibu-shi, Saitama-ken (JP)

(**) Term: **14 Years**

(21) Appl. No.: **29/235,790**

(22) Filed: **Aug. 8, 2005**

(30) **Foreign Application Priority Data**

Feb. 10, 2005 (JP) 2005-003488

(51) **LOC (8) Cl.** **14-02**

(52) **U.S. Cl.** **D14/420**

(58) **Field of Classification Search** D14/424,
D14/420, 425, 389; 235/462.11, 462.41,

(57) **CLAIM**

We claim the ornamental design for a document scanner, as shown and described.

DESCRIPTION

FIG. 1 is a front view of a document scanner showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.

1 Claim, 4 Drawing Sheets

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 555,652 S
APPLICATION NO. : 29/235790
DATED : November 20, 2007
INVENTOR(S) : Teruhiko Kitamura et al.

Page 1 of 1

It is certified that error appears in the above-identified patent and that said Letters Patent is hereby corrected as shown below:

ON THE TITLE PAGE ITEM [75] INVENTORS

“Kazuhikde Sigiyama” should read --Kazuhide Sugiyama--

Signed and Sealed this
